Term of patent 14 years

Int. Cl. D24—01

U.S. Cl. D24—1 B

FIG. 1

FIG. 2

FIG. 3

FIG. 1 is a front perspective of the dental console showing my new design;

FIG. 2 is a top plan view of the dental console of FIG. 1;

FIG. 3 is a side elevation of the dental console of FIG. 1;

FIG. 4 is a front perspective view of a modified embodiment illustrated in FIG. 1;

FIG. 5 is a plan view of the dental console shown in FIG. 4; and

FIG. 6 is a side elevation of the dental console shown in FIG. 4.

The front panels of the dental console illustrated in both embodiments are shaded to show contrasting color.

This application is a continuation-in-part of design applications Ser. Nos. D-118,581 and D-118,582, filed Feb. 24, 1971.

I claim:

The ornamental design for a dental console, substantially as shown.
